UNITED STATES PATENT OFFICE.

LOUIS B. PRAHAR, OF NEW YORK, N. Y.

GAS-LIGHTER.

No. 897,780.

Specification of Letters Patent.

Patented Sept. 1, 1908.

Application filed November 19, 1907. Serial No. 402,874.

To all whom it may concern:

Be it known that I, LOUIS B. PRAHAR, a citizen of the United States, and a resident of the city of New York, borough of Brooklyn, in the county of Kings and State of New York, have invented a new and useful Improvement in Gas-Lighters, of which the following is a full, clear, and exact description.

The purpose of the invention is to provide 10 a very simple and economic form of portable gas lighter, in which a flame is created by manually directing alcoholic vapors to a catalytic igniter, in such manner as to effectually prevent the possibility of an explosion 15 or ignition of the vapor in the reservoir or storage chamber of the lighter.

The invention consists in the novel construction and combination of the several parts as will be hereinafter fully set forth and 20 pointed out in the claims.

Reference is to be had to the accompanying drawings forming a part of this specification, in which similar characters of reference indicate corresponding parts in all the figures.

Figure 1 is a side elevation of the improved lighter; Fig. 2 is a sectional side elevation thereof; and Fig. 3 is an enlarged longitudinal section through the cartridge end of the 30 lighter.

A represents the body of the lighter, which is in the form of a tube of any desired length and diameter, and the upper end 10 of this body tube is bent or inclined to one side; as 35 is shown in Figs. 1 and 2, but the said upper end of the body tube may be otherwise formed, and it may be provided with the usual key for operating the gas cock when so desired. An air bulb 11 of the usual valve 40 construction is located at the lower end of the body tube A. This air bulb may be at the extreme lower end of the body tube, but by preference the body tube is made to pass through the said air bulb, as is illustrated in 45 Figs. 1 and 2, and when the air bulb is so located, apertures 12 are made in that portion of the body tube surrounded by the said bulb. The lower end of the body tube when 50 the tube passes through the bulb, is closed in any suitable manner. The said body tube A may be in one piece, but by preference it is made in two sections a and a', so that it can be readily filled or be taken apart for storage, and the said sections a and a' are 55 connected by a rigid tubular coupling 14,

usually screwed into the sections, as is shown in Fig. 1. The greater portion of the interior of the body tube A is filled with a packing 15 of absorbent material, and this absorbent material is saturated with alcohol. 60

In connection with the body tube A, I employ a cartridge section B; this cartridge section may be attached to the body tube in any removable manner, for example, by means of a slip joint, as is shown in Fig. 3, or 65 by a screw connection, or its equivalent. A valve seat 16 in the form of a tube, is located in the said cartridge at its lower end, and the upper portion of the valve seat when the cartridge is in position on the body, partially 70 closes the upper end 10 of the body tube A, the complete closure being effected by a check valve 17 located in said seat, and this check valve opens in direction of the outer end of the cartridge B, but is normally held 75 seated by means of a spring 17^a bearing on said valve and against a suitable cage 17^b, or its equivalent, but I do not confine myself to any specific construction of the valve.

The cartridge B is provided between the 80 valve and its outer end with a series of openings 18, and opposite the said openings within the said cartridge, a catalytic igniter C is suspended in any approved manner. This igniter may be of any appropriate construc- 85 tion; as is shown, it consists of a bunch of wires c of finely divided platinum or like material, which possesses the property of becoming highly heated when exposed to gas. These wires are shown as being passed through 90 a ring body c', which in its turn has a link connection with a bolt 19, or its equivalent, that is screwed into the head portion of a cap 20, which closes the outer end of the cartridge and is removable therefrom. 95

In operation each time the bulb 11 is pressed and released by hand, air is taken in through the customary valve of the bulb and is forced into the body A of the lighter, thus the air is forced through the saturated mate- 100 rial 15 in the said body of the lighter and the alcoholic vapors are forced up the body tube, and opening the valve 17 pass to the igniter C which is rendered immediately incandescent, and in consequence the gas is ignited 105 and the flame is produced at the openings 18 in the cartridge, whereby to light the gas at a burner. The valve 17 closes as soon as the air and gas are forced past it, so that when the bulb 11 expands it is impossible to draw 110

down air into the reservoir of the body, and thus an explosion or ignition is avoided in the said reservoir or chamber of the body carrying the stored alcohol.

5 This lighter is exceedingly simple in its construction, it is durable, and is easily manipulated, and furthermore it is positive and certain in its action.

I desire to have it understood that the 10 valve shown is not absolutely necessary since an equivalent thereof may be employed, for instance the absorbent material may be carried up to a point near the catalytic igniter.

Having thus described my invention, I 15 claim as new and desire to secure by Letters Patent:

1. As an improved article of manufacture, a gas lighter consisting of a body tube having one portion provided with an air vent, and 20 another portion below the said vent provided with a filling of absorbent material adapted to be saturated with alcohol, a catalytic igniter contained entirely within the body tube opposite the said vent, and an air bulb 25 carried by the body tube at a point below its absorbent filling, and connections between said air bulb and the interior of the body tube whereby a light is automatically created

only upon pressing the said air bulb, and the flame produced is directed to said vent.

30

2. As an improved article of manufacture, a gas lighter consisting of a body tube having one portion provided with an air vent, and another portion below the said vent provided with a filling of absorbent material adapted 35 to be saturated with alcohol, a catalytic igniter contained entirely within the body tube opposite the said vent, and an air bulb carried by the body tube at a point below its absorbent filling, and connections between 40 said air bulb and the interior of the body tube whereby a light is automatically created only upon pressing the said air bulb, and the flame produced is directed to said vent, and a controlling means for the fuel supply located 45 between the absorbent filling and the catalytic igniter.

In testimony whereof I have signed my name to this specification in the presence of two subscribing witnesses.

LOUIS B. PRAHAR.
